[57] ABSTRACT

A device for holding a rug against movement upon an underlying carpet comprises two elastically interconnected substantially flat strips, one strip having pins extending from a face adapted to engage the underlying carpet and the other strip having pins extending from a face adapted to engage the superposed rug.

FIG. 7

1
RUG HOLDER

This invention relates to rug holders and is more particularly concerned with a rug-holding device adapted to secure a rug against relative movement with respect to an underlying carpet.

Wall-to-wall carpeting is becoming an increasingly common floor covering in homes, particularly apartments, and in many business premises. Often it is desired to cover portions of the wall-to-wall carpeting with throw rugs of various sizes in order to enhance the decorative appearance of the carpeted area or to provide protection for the carpet in locations subject to heavy traffic. When such rugs are merely laid upon the carpeting, they tend to wrinkle and to creep or "travel" across the carpet when they are stepped upon, with the result that they become displaced from their original and desired locations and they present an unattractive appearance because of such displacement, which usually occurs in random fashion. As a result, the necessity of having repeatedly to return the rugs to their intended positions is a continuous annoyance.

It is, of course, possible to secure the rugs by driving nails through them and through the underlying carpet into the floor. This procedure, however, has obvious disadvantages from the standpoint of damage to the carpet, the rug and the floor and it makes it very difficult to free the rug when it is desired to clean the rug and/or the underlying carpet. Furthermore, the supporting floor may be formed of a material, such as concrete, tile, or the like which does not readily lend itself to the reception of nails or like securing devices. In addition, nailing detracts from the appearance of the rug and, even with such nailing, it is difficult to hold the rug in a taut condition, free from wrinkles.

It is accordingly an object of this invention to provide a device for removably securing rugs to underlying carpets which holds the rug securely in place in relation to the carpet but which permits the rug to be readily and easily removed for cleaning or for changing its location on the carpet when desired.

It is another object of the invention to provide a holding device of the character indicated which engages only the rug and the carpet and does not require engagement with the supporting floor.

It is a further object of the invention to provide a rug-holding device which will hold the rug in a taut, flat condition at all times and which is completely invisible when in use.

Other objects of the invention will be readily apparent from the following detailed description of illustrative embodiments of the carpetsecuring device.

In accordance with the invention, there is provided a rugholding device which comprises a pair of elastically-interconnected substantially flat members, suitably in the form of strips or plates, one of which is adapted to engage and be secured to the back surface of the rug and the other of which is adapted to engage and be secured to the upper surface of the carpet underlying the rug. For engagement with the rug, the first plate or strip member, which will hereinafter be referred to as the "rug bar," is provided with pins extending from its upper surface. The second plate or strip member which will hereinafter be referred to as the "carpet bar," is provided with pins extending from its undersurface. The rug bar and the carpet bar are interconnected by elastic means, suitably coil springs or the

2

like, in generally co-planar relationship. A rug-holder, in accordance with the invention, can be engaged with each end of the rug to be secured or, as will be described below, the rug holder may be engaged with only one end of the rug, and the other end of the rug may be secured or held in place upon the carpet by other means.

A fuller understanding of the invention will be obtained from the following more detailed description of 10 the holding device, taken with particular reference to the accompanying drawing wherein,

FIG. 1 is a plan view of a holding device embodying features of the present invention;

FIG. 2 is a cross-sectional view taken approximately 15 along the line 2—2 of FIG. 1;

FIG. 3 is a phantom plan view of a rug fitted with two rug-holding units of the type shown in FIG. 1;

FIG. 4 is a plan view of an auxiliary rug-holding device adapted to be used in combination with a holding 20 unit of the type shown in FIG. 1 when only one of these units is being used.

FIG. 5 is a cross-sectional view taken approximately along the line 5—5 of FIG. 4.

FIG. 6 is a phantom plan view of a rug fitted with the 25 rug-holding unit of FIG. 1 and the auxiliary unit of FIG. 4; and

FIG. 7 is a cross-sectional view of a rug removably secured to an underlying carpet by means of the rug-holding units illustrated in FIGS. 1 and 4, as seen approximately along the line 7—7 of FIG. 6.

Referring to the drawing, and more particularly to FIG. 1, the rug-holding unit illustrated is indicated generally by reference numerical 10, and comprises the rug bar 12 in the form of a thin plate or strip provided 35 with rug engaging pins 14. The rug bar 12 can be of any convenient size, but it preferably is relatively thin, e.g., it has a thickness of about 1/16 inch, and may be formed from any convenient material which is strong and rigid, preferably metal and most preferably sheet steel. The rug bar 12 suitably has a width sufficient to accommodate at least two closely spaced rows of pins 14, typically about 1 inch, and it can have a length sufficient to extend across the major portion of the end or side of the rug to which it is to be applied, or it may have a shorter length so that two or more of the bars 12 can be aligned from side to side across the rug. At least two rows of pins are employed, but there can be more, if desired. The rows are typically apart about 1/2 in. and the pins in each row are typically spaced about 1 in. from each other. These spacings are of course merely illustrative, and may vary widely as will be obvious to those skilled in the art. Suitably, the pins in each row are staggered relatively to the pins in the other row, as illustrated in FIG. 1. Cooperating with the rug bar 12 is the carpet bar 16 which may also be of any convenient dimensions, but which is advantageously approximately the same size as the rug bar. The carpet bar 16 has the carpet engaging pins 18 extending from its lower surface. The pins 14 extending from the upper surface of the rug bar can be at right angles to the bar 12, but preferably they are inclined at an acute angle of at least about 30° in the direction of the carpet bar 16. The pins 18, extending from the lower surface of the carpet bar 16, are suitably also acutely inclined, e.g., at an angle of at least about 30°, in the direction of the rug bar. The pins can be of any convenient structure, e.g., they can be thin, sharp nails frictionally or

adhesively or otherwise, e.g., by soldering or spot welding, secured at the desired angle in the strips or plates holding them. Suitably the pins extend through holes in the strips. Alternatively, the pins can be integrally connected to the strips, e.g., they can be formed by stamping, punching or other metal-working procedure. The pins can be of any convenient length so that they will firmly engage with the rug and carpet, but they preferably should not be so long they will extend through the carpet and mar the underlying supporting surface nor extend through the rug to cause annoyance to persons walking on the rug. Typically, the pins extend about $\frac{1}{4}$ inch to $\frac{1}{2}$ inch from the surface of the bar with which they are associated. The pins can extend the same distance from both bars or they can extend different distances. Ordinarily, although not necessarily, the pins in the rug bar which are to engage the overlying rug extend a lesser distance, e.g., $\frac{1}{4}$ inch or less, than the pins in the carpet bar.

A feature of the invention is that the plates or strips 12 and 16 are elastically interconnected. In the embodiment illustrated, this elastic interconnection takes the form of steel coil springs 20 engaged, e.g., in holes 23 and 24, with bars 12 and 16, respectively. It will be apparent that the invention is not limited to the use of springs although they are preferred, and that other elastic interconnecting means could be employed. Furthermore, while the spring-holding holes 23 and 24 are shown on the near sides of strips 12 and 16, it will be apparent that they can be formed on the far sides of the strips and that the springs 20 can be provided with extensions, e.g., in the form of hooks or the like not shown, which may overlie or underlie the strips, for engaging in such holes.

As illustrated in FIG. 7, when a rug-holding unit 10 is to be used, the bar 12 is engaged by means of its pins 14 with the underside of a rug 26. The end of the rug is then folded back and the pins 18 of the carpet bar 16 are then engaged with the carpet 28 while placing the elastic means under tension. The folded part of the rug is then laid flat. The process can then be repeated at the other end of the rug with another rug-holding unit 10. This results in the rug 26 being firmly, but removably, secured to the carpet 28 in a taut, flat condition, resistant to wrinkling and displacement when walked upon. FIG. 7 shows the units 10 adjacent the ends of the rug 26; they can be engaged along the sides of the rug, or even diagonally across the corners of the rug. FIG. 7 shows the rug securing units of the invention causing an exaggerated upward deflection of the carpet in order to emphasize the relative relationships but ordinarily the units will merely sink into the pile of the underlying carpet and will cause little or no deflection of the rug.

As previously mentioned, the effective securing of the rug to the carpet can also be realized by using a rug-holding unit 1 only at one end of the rug if the other end of the rug is effectively secure to the underlying carpet. For this purpose there is preferably used a holding device of the type shown in FIG. 4 which comprises a holder unit 30 formed from a plate or strip which can be of any dimension, but which is advantageously of the same size and shape as each of bars 12 and 16, and is provided with pins 32 extending from its upper surface and with pins 34 extending from its lower surface, the pins 32 and 34 being inclined in opposite directions at acute angles, e.g., of at least about 30° . Typically, the pins extend the distances referred to above in connec-

tion with the carpet bar and the rug bar and ordinarily, although not necessarily, the pins for engaging the rug will extend less far than the pins adapted to engage the carpet. When the holder unit 30 is used, it is engaged with the rug 26 with the pins 32 directed toward the free edge of the rug and the pins 34 are then engaged with the carpet 28. Then the unit 10 is applied to the opposite end of the rug in the manner previously described and, when the bar 16 is engaged with the carpet while the springs 20 are under tension, the rug will be firmly but removably, secured in relation to the carpet against wrinkles, lateral movement or displacement of any kind.

When it is desired to clean the rug and/or the carpet, it will be apparent that the securing devices described above can be readily disengaged from both the rug and the carpet, and they can as readily be reused when it is again desired to secure the rug to the carpet.

It will be obvious that various changes and modifications in the structure of the specific embodiments of the invention described above and illustrated in the drawing will be readily apparent to those skilled in the art. It is intended, therefore, that all matter contained in the foregoing description and in the drawing shall be interpreted as illustrative only and not as limitative of the invention as defined in the appended claims.

I claim:

1. A device for removably securing a rug to an underlying carpet to inhibit relative movement between the rug and the carpet which comprises, in combination, a first substantially flat elongated member having pins extending from a face thereof adapted to engage the superposed rug, a second substantially flat elongated member having pins extending from a face thereof adapted to engage the underlying carpet, said first member and said second member being in generally coplanar relationship, and elastic means interconnecting the end portions of said first and second members in said generally co-planar relationship with the pins of the first member extending upwardly and the pins of the second member extending downwardly when the two members are horizontally disposed.
2. A device as defined in claim 1, wherein the pins in said first and second members extend at an acute angle, with the pins in the first member and the pins in the second member being inclined in opposite directions.
3. A device as defined in claim 1, wherein each member contains its pins arranged in at least two rows, with the pins in one row being staggered with respect to the pins in an adjacent row.
4. A device for removably securing a rug to an underlying carpet to inhibit relative movement between the rug and the carpet which comprises a first substantially flat member having pins extending from a face thereof adapted to engage the superposed rug, a second substantially flat member having pins extending from a face thereof adapted to engage the underlying carpet, and elastic means interconnecting said first and second members in generally co-planar relationship with the pins extending from opposite faces of said members, and a third flat member having pins extending from both its faces, the pins extending from one face being adapted to engage the superposed rug and the pins extending from the opposite face being adapted to engage the underlying carpet, the pins in said third flat member extending at an acute angle, with the pins extending from the two faces being inclined in opposite directions.
